UNITED STATES PATENT OFFICE.

LEWIS M. WILDE, OF NORTH WALPOLE, NEW HAMPSHIRE.

SANCTUARY-LAMP.

959,412.

Specification of Letters Patent. Patented May 24, 1910.

Application filed September 11, 1909. Serial No. 517,191.

To all whom it may concern:

Be it known that I, LEWIS M. WILDE, a citizen of the United States, and a resident of North Walpole, in the county of Cheshire and State of New Hampshire, have invented 5 a new and Improved Sanctuary-Lamp, of which the following is a full, clear, and exact description.

The invention is an improvement in sanctuaries lamps and has in view a motor-driven 10 mechanism to trim the carbon from the lamp wick during the burning of the lamp, the said mechanism being inaudible in action and assembled compactly with the lamp proper.

Reference is to be had to the accompanying drawings forming a part of this specification in which similar characters of reference indicate corresponding parts in all the 15 views.

Figure 1 illustrates a sanctuary lamp as suspended from the ceiling and embodying my invention; Fig. 2 is a plan of the burner and assembled motor-driven wick-trimming mechanism; and Fig. 3 is a side view of the 20 same partly in central vertical section.

Referring more particularly to Figs. 2 and 3, wherein are shown my improvements in detail, two disks or plates 5, 5, arranged 25 one above the other in spaced relation and rigidly secured together by the thimble bolts 6, and a plate 7 arranged below and similarly secured to the plates above, constitute the frame of a clock mechanism. The plate 30 7 is confined to one side of the frame and carries a spring motor 8, the winding shaft of which projects below the frame and is provided with a gear 9 meshing with a pinion 10 arranged on the winding stem 11.

The motor extends some distance above the bottom plate 5 of the frame, where it is provided with a relatively large driving gear 35 12 meshing with a much smaller gear 13 secured to a vertical shaft 14, the shaft projecting above the top plate 5 of the frame, where it has an attached gear 15. The shaft 14 is further provided with a gear 16 which drives an escapement mechanism through the train of gearing, as shown in dotted outline in Fig. 2.

Passing centrally through the plates 5, 5 and rigid therewith is a wick tube 17, the same standing some distance above the top plate 5, where it is counterbored and internally threaded to receive the 45 50 55 threaded boss on the lower end of a tubular burner 18, the external diameter of the

burner adjacent to the wick tube being slightly greater than the diameter of said tube, to provide a shoulder 19. Between this shoulder and the top plate 5 is the hub 60 portion of a gear 20 journaled on the wick tube and in mesh with the gear 15, the gear 20 having a vertical socket 21 projecting from its upper face. The socket 21 receives the shaft of a wick trimmer 22, the trimmer 65 having an overhanging trimming finger 23 at its upper end and adjustably secured at different elevations in the socket by a set-screw 24.

In Fig. 1 I have shown a conventional 70 type of mounting for the lamp, the same embodying a pendant or vessel 25 suitably suspended from the ceiling and having a fuel tank arranged above the same and feeding the wick tube through one of the tubular hangers 27. The burner trimmer at the top of the upper plate 5 is supported in the vessel to stand above the top thereof, and inclosed by a chimney 28. Below the top plate 5, the structure shown in Fig. 3 is 75 inclosed by the upper portion of the vessel, the latter having an opening in the side, through which the stem 11 is accessible for winding the motor.

Having thus described my invention, I 80 claim as new and desire to secure by Letters Patent:

1. The combination of frame plates rigidly secured together in spaced relation, a motor carried by said plates, a vertical wick 90 tube passing centrally through the frame plates and having a burner, a vertical shaft journaled in the frame plates and driven from the motor, having an attached gear arranged above the upper plate, an escape- 95 ment mechanism driven from the vertical shaft, a gear journaled on the wick tube and in mesh with the first mentioned gear, having a socket, and a wick trimmer vertically adjustable in said socket and having a trimming finger overhanging the burner.

2. The combination of frame plates rigidly secured together in spaced relation, a vertically arranged wick tube passing through said plates and having a burner 105 above the upper plate, a wick trimmer revolute about the burner, and a clock mechanism carried by said plates and operatively connected to the wick trimmer.

3. The combination of an upper, lower 110 and intermediate frame plate rigidly secured together in spaced relation, a wick

tube passing centrally through the intermediate and upper plate and having a burner at the upper end portion thereof, a motor carried on the upper and lower plate and extending above the intermediate plate, a winding mechanism for the motor, arranged below the lower plate, a wick trimmer revolute about the burner, means for driving the wick trimmer from the motor, and an escapement mechanism arranged between the upper and intermediate plates and driven from said means.

4. The combination of frame plates rigidly secured together in spaced relation, a wick tube passing vertically through said plates, a motor-actuated mechanism carried by the plates and having a driven member journaled on the wick tube, and a wick trimmer carried by said member.

5. The combination in a lamp, of a

burner, a wick trimmer revolute about the burner and normally engaging the wick, and a clock mechanism operatively connected to the wick trimmer to move the trimmer continuously over the wick.

25

6. The combination of a pendant, a lamp arranged within the pendant having a burner projecting thereabove, a wick trimmer revolute about the burner, a motor operatively connected to the wick trimmer, and means to wind the motor from the outside of the pendant.

30

In testimony whereof I have signed my name to this specification in the presence of two subscribing witnesses.

LEWIS M. WILDE.
